UNITED STATES PATENT OFFICE.

HERBERT K. VANDEWALKER, OF PAMELIA FOUR CORNERS, NEW YORK.

HAY-CARRIER.

SPECIFICATION forming part of Letters Patent No. 311,545, dated February 3, 1885.

Application filed November 1, 1884. (No model.)

To all whom it may concern:

Be it known that I, HERBERT K. VANDEWALKER, a citizen of the United States, residing at Pamelia Four Corners, in the county of Jefferson and State of New York, have invented a new and useful Improvement in Hay-Carriers, of which the following is a specification, reference being had to the accompanying drawings.

10 My invention relates to hay-carriers; and it consists in the construction and novel arrangement of parts, as will be hereinafter fully described, and particularly pointed out in the claims.

15 In the drawings, Figure 1 is a view in perspective of a hay-carrier embodying the improvements of my invention. Fig. 2 is an elevation with a portion of the side broken away to show the internal mechanism. Fig. 3 is a 20 view in perspective of the double pulley and its serrated cam and toothed dog. Fig. 4 shows the cam and dog tripped. Fig. 5 is a view in perspective showing the last part of the load of hay in the act of being elevated from the 25 rack. Fig. 6 is a plan of the track. Fig. 7 is a view of one of the slings employed with this carrier. Fig. 8 is a plan view of a portion of the track, showing the carrier thereon: Fig. 9 is a bottom plan of the carrier and a portion of the track, and Fig. 10 is a side elevation of two of the rafters and the supports for 30 one end of the track. Fig. 11 is a vertical longitudinal section through the carrier.

Referring by letter to the accompanying 35 drawings, A designates the track, which is suspended by hangers B from the rafters of the barn. This track is provided with a stop-rod, C, which the trip of the carrier engages when drawn over the portion of the track where said 40 stop-rod C is located.

C' is the trip-rod, which strikes the arm C² of the serrated dog D when the carriage moves over said trip-rod C'. The carrier-frame is suspended from two axles mounted on four 45 flanged wheels which travel on the track A. Below the serrated dog D the carrier-frame is provided with a friction-pulley, D', over which the hoisting-rope D² runs, and the serrated dog D bites upon and holds the hoisting-rope 50 D² against the bottom of car, when the pull on the hoisting-rope ceases and holds the hoisting-rope at the point to which it has been

drawn until the trip-arm C² strikes the trip-rod C' and releases the bite of the dog D. At the end opposite the dog D the carrier is provided with a pivoted bifurcated catch, F, between the arms of which the inner end of an open bail, F', is pivoted. The other end of said bail F' is pivoted by a staple, F², to the under face of the carrier-frame. Between its arms the bifurcated catch F is provided with a link, F³, to which one end of the hoisting-rope D² is connected. The hoisting-rope D² runs down through one side of a double pulley, G, and up through the other side, thence 65 through the open bail F', and over the friction-pulley D', and under the serrated dog D', and thence over a pulley, H, at the end of the track, out of the barn, and over a pulley, H', secured to a stake, H², and thence to the whiffletree H³. The double-pulley block G' of the double pulley G is provided with a pivoted serrated dog, I, which engages a transverse partition, G², in said pulley-block G', and to this dog I is connected a trip-rope, J, which 75 runs over a pulley, K, at the end of the track opposite or farthest from the pulley H, and thence down to within reach of the operator.

In using this hay-carrier no horse-fork is required, but in lieu thereof three slings, S, are 80 employed, and are constructed as shown in Fig. 7. The slings consist each of a single piece of rope doubled and wrapped with wire T, to form a loop, U, and wrapped also at each end to prevent them from fraying. The manner of using these loops is as follows: The first sling is laid on the bottom of the rack and spread out, the ends permitted to hang out. The hay is built upon the wagon until one-third of the load has been built up, when a 90 second sling is spread upon the hay, and the building of the load is continued until a second third has been added, when another sling is spread, and the last third of load is added. When the barn has been reached, and the hay-carrier is to be used, the loop of the upper sling is placed in engagement with the hook on the single-pulley block X, and the wired ends of the upper sling are inserted between the partition and the serrated dog in the double-pulley block, and the horse attached to the hoisting-rope. As the horse moves off, the load is first lifted from the rack and drawn up into engagement with the carrier, which is at 95 100

this time stationary, the trip of the carrier being in engagement with stop-rod C. When the block of the double pulley strikes the bail F', the bifurcated catch is released from the 5 stop-rod and the carrier may be moved along to the desired place, when the trip-rope should be pulled to release the bite of the serrated dog upon the wired ends of the sling, which will permit the hay to fall from the sling. The 10 second and third slings are lifted in the same manner, and the rack is thus unloaded.

Having thus fully described my invention, what I claim as new, and desire to secure by Letters Patent of the United States, is—

- 15 1. The combination, with the carrier-frame having four flanged wheels, and provided with the friction-pulley D', of the pivoted bail F', the pivoted bifurcated catch F, the serrated dog D, on the pivoted trip-arm C', as set forth.
- 20 2. The combination, with the carrier-frame, its pulley D', pivoted bail, serrated dog, and pivoted bifurcated catch F, of the hoisting-rope D', the double-pulley block with its partition, pulleys, and trip-rope, and the single 25 pulley and its open ring, substantially as specified.

3. The combination, with the carrier-frame, its pulley D', pivoted bail, serrated dog, and pivoted bifurcated catch F, of the hoisting-rope D', the double-pulley block with its partition, pulleys, and trip-rope, and the single pulley, its open ring, and the wired sling, substantially as specified. 30

4. As a new article of manufacture, the herein-described sling, consisting of a piece of rope 35 wired to form a loop at its middle and wired at each end, substantially as specified.

5. The combination, with the suspended track having the stop-rod and trip-rod and pulleys, of the carrier-frame mounted on 40 flanged wheels, and provided with the pulley D', and the serrated dog, the pivoted bail, the bifurcated catch, and the operating-ropes, substantially as specified.

In testimony that I claim the foregoing as 45 my own I have hereto affixed my signature in presence of two witnesses.

HERBERT K. VANDEWALKER.
